(57) **CLAIM**

The ornamental design for a collapsible truck tailgate table for construction plans, as shown and described.

DESCRIPTION

FIG. 1 is a perspective view of a collapsible truck tailgate table for construction plans embodying the design of the present invention, showing the invention in a raised position. The broken line showing of environmental structure is for illustrative purposes only and forms no part of the claimed design.

FIG. 2 is a front elevational view of the invention in the raised position;

FIG. 3 is a rear elevational view of the invention in the raised position;

FIG. 4 is a side elevational view of the invention in the raised position;

FIG. 5 is a top plan view of the invention in the raised position; and,

FIG. 6 is a bottom plan view of the invention in the raised position.

1 Claim, 4 Drawing Sheets**FIG.1.**

FIG. 2

FIG. 3.

FIG.4.

FIG.5.

FIG. 6.
